UNITED STATES PATENT OFFICE.

JAMES C. VAN CLEAVE, OF MALVERN, ARKANSAS.

FENCE.

SPECIFICATION forming part of Letters Patent No. 369,571, dated September 6, 1887.

Application filed May 12, 1887. Serial No. 237,979. (No model.)

To all whom it may concern:

Be it known that I, JAMES C. VAN CLEAVE, a citizen of the United States, residing at Malvern, in the county of Hot Spring and State 5 of Arkansas, have invented a new and useful Improvement in Fences, of which the following is a specification.

My invention relates to improvements in portable fences; and it consists in a certain 10 novel construction, fully described hereinafter, and specifically pointed out in the claim.

In the drawings, Figure 1 is a perspective view of a section of the fence. Fig. 2 is a vertical transverse section through one of the 15 posts. Fig. 3 is a detail section through the sill.

Referring to the drawings, A designates a horizontal transverse sill, at the center of which, on the upper side, is formed a notch, B, the bottom of which notch is ridged to form a saddle, B'.

C designates the post, formed of two vertical parallel planks, D D, provided at the upper ends, on the outer sides, with the notches d d. 25 Near the outer ends of the sill are formed the inclined grooves or notches a a, and in the said notches are secured the lower ends of the clamping or brace bars E, which are adapted to be received near the upper ends in the notches 30 d in the upper ends of the uprights D.

F designates the horizontal rails of the fence, and to secure the same in place nail the ends thereof to one of the uprights D, place the other upright in position on the other side of 35 the ends of the rails, and cause the clamping-bars to engage in the notches d.

The notch B in the center of the sill is made to fit the lower ends of the uprights very tightly when the rails are between them, and 40 when the upper ends of the said uprights are drawn together the rails are firmly clamped in place between the uprights.

The clamping-bars are so arranged as to necessitate their being drawn forcibly apart 45 against the spring of the wood, to enable the

upper ends of the uprights to be placed therebetween, and consequently when the said clamping-bars are released they spring tightly into the notches d and hold the post firmly in position.

The ends of the rails are nailed or otherwise secured to the uprights D; but the same rail is never secured at opposite ends to two uprights on the same side of the fence. One end of each rail is secured to the near upright of one 50 post and the other end to the far upright of the next post. This construction allows the fence to accommodate itself to the irregularities of the ground on which it is built.

The lower ends of the uprights are notched 60 to fit the saddles B' in the notches B, to prevent the post from slipping out of place.

It will be seen that the fence as described is portable, the sills being adapted to rest on the surface of the ground, and by simply spreading the upper ends of the clamping-bars the 65 fence may be taken apart.

Having described my invention, I claim—
As an improvement in fences, the combination 70 of the base or sill having the inclined grooves a a in their opposite sides, near their opposite ends, and the central notch, B, in its upper side, the base of said notch B having the longitudinal ridge B', the braces having their lower ends secured in the grooves a a, the vertical 75 parallel planks D D, secured in the notches B and having their lower ends notched to fit over the ridge B', and provided with the notches d in their upper outer edges to receive the upper portion of the braces, and the 80 rails secured between the planks D D, substantially as specified.

In testimony that I claim the foregoing as my own I have hereto affixed my signature in presence of two witnesses.

JAMES C. VAN CLEAVE.
